COMBINED ACTUATOR BUTTON AND INDICA- TOR PLATE OR SIMILAR ARTICLE

John A. Cox, Jr., Freeport, Ill., assignor to Honeywell
Inc., a corporation of Delaware

Continuation of design applications Ser. Nos. 73,765,
73,766, and 73,767, Mar. 1, 1963. This application
Mar. 23, 1964, Ser. No. 79,113

Term of patent 14 years

(Cl. D26—13)

Fig. 3

FIG. 6

FIGURE 1 is an exploded perspective view of a combined actuator button and indicator plate or similar article, showing one form of my new design wherein the actuator button is a push button and wherein the periphery of the actuator button is smooth and the top surface is concave;

FIGURE 2 is a side elevational view of the form shown in FIGURE 1, the other sides having substantially the same appearance;

FIGURE 3 is a fragmentary cross-sectional view of the form shown in FIGURE 1 showing the depression in the top of the actuator button;

FIGURE 4 is a perspective view of a combined actuator button and indicator plate or similar article, showing another form of my new design wherein the actuator button is a rotary selector and wherein the periphery of the actuator button is provided with longitudinal flutes and the top surface is flat;

FIGURE 5 is a perspective view of a combined actuator button and indicator plate or similar article, showing another form of my new design wherein the actuator button is a combined rotary selector and push button and wherein the periphery of the actuator button is provided with longitudinal flutes and the top surface is concave; and

FIGURE 6 is a fragmentary cross-sectional view of the form in FIGURE 5 showing the concave top surface of the actuator button.

The essential features of my design comprise a generally rectangular parallelepiped appearing indicator plate and an actuator button centrally located with respect thereto and extending outwardly therefrom. The area beneath the transparent indicator plate is sectioned into quadrants for color or other indicia. The bottom or back sides, not shown, of my design is conventional.

The dominant features of my new design are shown in solid lines in the drawing.

This application is a continuation of my three co-pending applications, Serial Numbers D. 73,765, D. 73,766, and D. 73,767, all filed March 1, 1963, now abandoned.

I claim:

The ornamental design for a combined actuator button and indicator plate or similar article, as shown and described.
